PONTOON

Leroy R. Shep, Los Angeles, Calif.

Application November 1, 1943, Serial No. 508,457

12 Claims. (Cl. 114—54)

1

My invention relates to a pontoon, and more particularly to a pontoon adapted to displace water and provide buoyancy for ships.

An object of my invention is to provide buoyant means by which sunken vessels may be raised, damaged vessels may be kept afloat and listing ships may be righted.

Another object of the invention is to provide collapsible pontoon means that may be collapsed and placed under water in position prior to their being rendered buoyant.

A further object of the invention is to provide means for reducing the buoyancy of the pontoon as the sunken ship rises toward the surface of the water.

My invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawings merely show and the following description merely describes one embodiment of the present invention, which is given by way of illustration or example only.

In the drawings, like reference characters designate similar parts in the several views.

Fig. 1 is an elevation, partly in section, showing an embodiment of my foregoing invention.

Fig. 2 is an enlarged, broken section, taken on the line 2—2 of Fig. 1.

Fig. 3 is an enlarged, horizontal, fragmentary section taken on the line 3—3 of Fig. 1.

Fig. 4 is an enlarged, fragmentary section taken on the line 4—4 of Fig. 1.

Fig. 5 is a reduced perspective view of said embodiment.

Referring more in detail to the drawings, the reference number 6 indicates a top plate reinforced around its edges by angle irons 7. A plurality of adjustable clamps 8 are mounted on the top plate 6. Each clamp comprises a stationary jaw 9 and a relatively movable jaw 10 that is controlled by an adjusting screw 12. The jaws 9 and 10 have complementary recesses to engage flanges of I-beams, such as shown at 13. The I-beams 13 are shown in the drawings as supporting a deck plate 14.

Normally vertical, corner angle irons 15 are arranged to depend from the top plate 6 at the corners thereof. Spaced below the top plate 6

5 by means of the corner angles 15, is an obtuse-angular band 16. The upper edge 17 of the band 16 is fastened to the lower ends of a series of wire rope strands 18 that depend from the top plate 6. The upper ends of the wire rope strands 18 are fastened to the top angle irons 7. The rigid corner pieces 15 maintain the strands 18 taut.

10 A tapering, flexible web of wire rope strands 19 has the upper ends of such strands fastened to the lower edge of the angularly bent band 16. The lower ends of such strands 19 are respectively engaged by S-hooks 20, as best shown in Fig. 4. These S-hooks in turn hook into a bottom 15 ring 21.

10 The upper and lower ends of the wire rope strands 18 and the upper ends of the wire rope strands 19 are fastened to the angle irons 7 and 16 by suitable means. An effective means is 20 shown in Fig. 3, to wit, U-bolts 22 that are fastened in place by nuts 23. The wire rope strands 18 and 19 are clamped in the bend of the U, as shown in Fig. 3, as the nuts are screwed home.

Arranged within the aforescribed frame-work 25 is a light, flexible, substantially waterproof and airproof, collapsible container 24, which, when expanded, is approximately the size and shape of the interior of the frame-work, to wit, rectangular at the top and tapering in the lower portion down to a breather opening 25 at the bottom thereof. This container or bag 24 may be of any suitable material that will have the foregoing properties. Suggested therefor is a canvas or No. 1 cotton duck bag treated with suitable 30 flexible plastic (known to those skilled in this art as "plastic dope"), to render it substantially waterproof and airproof. The canvas is preferably 35 liberally covered with said material, and the sections thereof may be sewn together in a tongue-and-groove construction, which is likewise known to those skilled in the art.

An air line 26 connects with the interior of the bag, such as through a side thereof (see Fig. 2). The air line connects with suitable pump air compressor or pressure tank means (not shown) at 45 the surface of the water, for supplying air pressure within the bag when desired. A valve 27 is also conveniently provided to release some of the pressure as the pontoon nears the surface, so as to raise the ship gradually and steadily.

50 In the use of my device, while the bag 24 is in a collapsed position, the clamps 8 are arranged to grip a part of a ship, such as I-beams therein. When as many pontoons as desired have been placed in position with their rings 21 and open-

ings 25 at the under sides thereof, they are ready to have the air pressure applied in the bags.

As the air is introduced into the bags, a pocket of air is entrapped inside at the top of each bag. As more air is introduced into the bag, the buoyancy of the pontoon is correspondingly increased, and as more air is introduced, more water is displaced and driven out from the bag through the opening 25.

Then, as the ship rises, the entrapped air in each bag may be progressively released by means of the valve 27. As the air pressure is decreased in the bag 24, more water flows up into the bag through the opening 25. Thus, it can be seen that the opening 25 acts as a breather for the bag, to equalize the pressure of the water inside and outside the bag.

Lift of the bag, when it contains air pressure, is exerted upon the top plate 6. Since the arrangements of the wire rope strands 18 and 19 substantially conform to the shape of the bag 24, these strands maintain the bag in its therewith conforming position and maintains the breather opening 25 underneath the body of the bag.

There are many uses of the present invention and many adaptations can be made of the present pontoon. In use, of course, a larger number of these pontoons may be placed at the lower side of a listing vessel. Moreover, the present pontoons may be applied to a ship before it enters dangerous waters, in order that the pontoons may be used when needed, to maintain the ship afloat despite damage. Moreover, these units may be used exteriorly of a ship by connecting pairs together, i. e., running the connecting means under the keel of the ship and then fastening the ends of the connecting means to respective pontoons at either side of the ship. These can be arranged where the greatest lift is desired, such as forward, midship or at the after end. These suggestions pertain to the use of the invention and are believed clear to those skilled in the art without further illustration.

While I have illustrated and described what I now regard as the preferred embodiment of my invention, the construction is, of course, subject to modifications without departing from the spirit and scope of my invention. I, therefore, do not wish to restrict myself to the particular form of construction illustrated and described, but desire to avail myself of all modifications that may fall within the scope of the appended claims.

Having thus described my invention, what I claim and desire to secure by Letters Patent is:

1. In a pontoon, a flexible bag having substantially airproof and waterproof walls and having a breather opening in the lower portion thereof, wire rope strands around the upper part of the bag confining same, frames respectively connecting with the strands at spaced points, rigid spacing means maintaining the frames in spaced relation and maintaining the strands substantially taut, flexible wire rope strands connected with one of the frames and yieldingly enclosing the lower portion of the bag adjacent the breather opening, and means to regulate the inflow and outflow of air pressure into and from the top of the bag.

2. In a pontoon, a flexible bag having substantially airproof and waterproof walls and having a breather opening in the lower portion thereof, wire rope strands around the upper portion of the bag confining same, spaced frames, means clamping the strands to the frames, means to hold the frames spaced and the strands taut,

a flexible web of wire rope strands enveloping the lower part of said bag and connected at one end to one of said frames and at the other end converging to a means for defining said breather opening and means to regulate the inflow and outflow of air pressure into and from within the bag at a point above said breather opening.

3. In a pontoon, a cage member composed of substantially rectangular frames rigidly held in spaced relation, one of said frames having a depending, flexible web comprised of convergent strands secured to a means defining an enclosure in the bottom thereof, a collapsible bag substantially conforming to the interior shape of the cage and its depending web, the bag having a flexible, substantially airproof and waterproof body and having a breather opening in the lower portion thereof coinciding with the enclosure in said web, and means connected to regulate the inflow and outflow of air pressure into and from within the bag at a point above said breather opening.

4. In a device of the character disclosed, a pair of substantially rectangular frames, means to hold said frames rigidly spaced, a plate secured to the upper of said frames, a series of wire strands between and connecting said frames, a series of wire strands connected at one end to and depending from the lower of said frames, said strands converging below and at a point removed from said lower frame, an eye to which the other ends of said strands are connected, said converging strands forming a flexible envelope, and fluid retaining container within said frames, said container having a tapering portion fitting within said converging envelope and provided in the end thereof with an opening which registers with said eye.

5. In a device of the character disclosed, a substantially rectangular enclosure of rigidly related members, comprising a top frame and a bottom frame, and interconnecting members for uniting said frames into a rigid structure, strands secured to and tautened between said top and bottom frames, a plate conveying said top frame, a series of strands secured to and depending from said lower frame, said strands converging at their ends, an eye to which said ends are secured, and a flexible fluid pressure container within said enclosure and having a tapering bottom portion within said converging strands and provided with a breather opening which registers with said opening defined by said eye, and means to regulate the fluid pressure within said container.

6. In a device of the character disclosed, an envelope comprised of a rigid upper section and a flexible converging lower section provided with an eye in the bottom thereof, and a fluid pressure container fitted within said envelope, said container having an opening in the bottom thereof registering with, and the converging ends of said container fastened to, said eye.

7. In a pontoon, a flexible, substantially airproof and waterproof bag having upper and lower portions, the lower portion converging to a breather opening that is open at all times to admit water into the bag, substantially rigid means on the upper portion of the bag, within which upper portion air pressure is initially entrapped, spaced frames, means between the frames confining the upper portion of the bag flexible grid means connected to one of said frames and enclosing the lower, converging portion, and means to regulate the inflow and outflow of air

pressure into and from within the bag at a point substantially above said breather opening.

8. In a pontoon, a flexible, substantially airproof and waterproof bag, substantially rigid means on the bag, the bag having a breather opening in its lower portion, anchoring means arranged to fixedly connect with a fixed part of the work to be buoyed up, the anchoring means having a substantially rigid connection with said rigid means, and means to regulate the inflow and outflow of air pressure into and from within the bag at a point substantially above said breather opening.

9. In a pontoon to buoy up work, a flexible, substantially airproof and waterproof bag, substantially rigid means on the bag, the bag having a breather opening in its lower portion, clamping means disposed to fixedly clamp upon a fixed part of the work, the clamping means having a substantially rigid connection with said rigid means, and means to regulate the inflow and outflow of air pressure into and from within the bag at a point substantially above said breather opening.

10. In a pontoon to buoy up work, a flexible, substantially airproof and waterproof bag having upper and lower portions, the lower portion having a breather opening that is unobstructed at all times, substantially rigid means on the upper portion of the bag, means to connect the rigid means with the work, and means connected with the bag to regulate the inflow and outflow of pressure into and from the bag at a point between the rigid means and the breather opening.

11. In a pontoon to buoy up work, a flexible, substantially airproof and waterproof bag having upper and lower portions, the lower portion converging to a breather opening, relatively rigid means on the upper portion of the bag, the rigid means extending to the greatest cross-sectional area of the bag, means to connect the rigid means

with the work, and means connected with the bag to regulate the inflow and outflow of pressure into and from the bag at a point between the rigid means and the breather opening.

- 5 12. In a pontoon, a bag having an opening in the bottom thereof to admit water, spaced frames, a plate on the top of the bag and connected to one of said frames, rigid means between the frames confining the upper portion of the bag, flexible means confining the lower portion of the bag, said flexible means being connected to the other of said frames, and means to supply and remove fluid pressure from the top of the bag.
